FEED CHUTE AND CONTROL PANEL CARRY- ING MEMBER FOR A MICROFILM RE- CORDER OR THE LIKE

Thomas R. Perzentka, Chicago, Ill., assignor to
Bell & Howell Company, Chicago, Ill., a cor-
poration of Illinois

Application November 12, 1948, Serial No. 149,604

Term of patent 14 years

(Cl. D61—1)

To all whom it may concern:

Be it known that I, Thomas R. Perzentka, a citizen of the United States, residing at Chicago, in the county of Cook and State of Illinois, have invented a new, original, and ornamental Design for a Feed Chute and Control Panel Carrying Member For a Microfilm Recorder or the like, of which the following is a specification, reference being had to the accompanying drawing, forming a part thereof.

In the said drawing—

Figure 1 is a perspective view of a feed chute and control panel carrying member for a microfilm recorder or the like embodying my new design;

Figure 2 is a top plan view of the same;
Figure 3 is a side elevation of the same; and
Figure 4 is a front elevation of the same.

I claim:

The ornamental design for a feed chute and control panel carrying member for a microfilm recorder or the like, as shown.

THOMAS R. PERZENTKA.
